UNITED STATES PATENT OFFICE.

ROBERT DERRY, OF SINGAPORE, STRAITS SETTLEMENTS.

CURING OF INDIA-RUBBER.

1,030,651.

Specification of Letters Patent. Patented June 25, 1912.

Application filed April 1, 1911. Serial No. 618,372.

To all whom it may concern:

Be it known that I, ROBERT DERRY, a subject of the King of England, residing at Singapore, Straits Settlements, have invented certain new and useful Improvements in the Curing of India-Rubber, of which the following is a specification.

This invention relates to improvements in the curing of india-rubber and refers more particularly to apparatus for coagulating and curing the latex of Pará rubber known as *Hevea-brasiliensis* and the latices of other Heveas and of other species of rubber producing plants or trees.

According to this invention in an apparatus for curing latex wherein it is exposed in a thin film to the action of smoke, there is employed in combination a heating and a smoke chamber or a heating chamber containing smoke, a supply of latex outside the heating and smoke chambers and an endless flexible band conveying a thin film of material into the chambers.

According to one modification of the present invention the parts of the apparatus are so arranged that the band continually removes the surface layer of latex out of the supply vessel into which said band dips.

Other features of the invention will be more readily understood from the following description which is that of one method of carrying the invention into effect, taken in connection with the accompanying drawings, in which—

Figure 1 is a longitudinal sectional elevation of the apparatus; Figs. 2 and 3 are front and side elevations respectively of a detail of the apparatus, and Fig. 4 is a detailed view of other parts of the apparatus.

A chamber bounded by walls A A¹ A² A³ comprises the heating and smoke-chamber wherein the latex is cured. The heat and smoke are generated in the furnace B situated at one end of the apparatus and are led through a flue B¹ to a smoke valve-chamber B² situated at the other end of the apparatus. The valve-chamber B² contains a damper or valve B³ shown in dotted lines in Fig. 1. An inclined pipe B⁴, preferably composed of a galvanized or sheet iron tube, is connected at one end by a conduit B⁵ with the chamber B². The pipe B⁴ is perforated on its under side with a number of small holes extending the entire length of the pipe. The conduit B⁵ is loosely mounted in the chamber B² so that it will adapt

itself to the movement of the pipe B⁴ which will be hereinafter referred to.

Situated below the pipe B⁴ is an inclined trough C having a draining pipe C¹, the latter discharging outside the main chamber.

The caoutchouc containing the latex is carried into the smoke and heat chamber by means of an inclined and endless band D. The band is supported at its upper end on a pulley D¹ inside the chamber. The pulley D¹ is carried in journals D² movable in guides D³ in a direction parallel with the stretches of the band. Secured to the journals D² is a cable or the like D⁴ passing over the pulley D⁵ and carrying at its free end a weight D⁶. The other end of the band D is carried over a pulley E situated outside the smoke-chamber; the two stretches of the band passing through orifices provided for that purpose in the wall A of the smoke-chamber.

Beneath the pulley E is a trough E¹ carrying a supply of latex. The trough E¹ is supported on a screw-rod E² passing through screw bearings E³ and E⁴. At the lower extremity of the screw-rod E² is rigidly secured a hand-wheel E⁵ so that by rotating the hand-wheel the trough may be either raised or lowered toward the band.

A latex-reservoir F preferably in the form of a closed tank having a lip F¹ is arranged at one side of the trough E¹ so that latex can be discharged into the trough from the reservoir.

In the illustrations, a crank-handle G is shown carrying a worm G¹ meshing with a worm-wheel G² the latter being rigidly secured to the shaft G³ carrying the pulley E. By rotating the crank-handle G, the pulley E is rotated and the band thereby moved. At one end of the shaft G³ is a pinion G⁴ which is geared through a gear-wheel G⁵ with another gear G⁶ carried on one end of a counter-shaft G⁷. At the other end of the counter-shaft a beveled gear-wheel G⁸ engages with a similar beveled gear-wheel G⁹ which is rigidly secured to a shaft carrying a worm G¹⁰. The worm G¹⁰ meshes with a worm-wheel G¹¹ rotatably mounted on a bracket G¹². A boss on the worm-wheel G¹¹ has an internal screw-thread meshing with a threaded rod G¹³ pivotally connected at G¹⁴ to the reservoir F. The shaft G³ and its attendant parts are supported as shown by a bracket G¹⁵.

Preferably the pulley E is secured to the

shaft G^3 by means of a clutch G^6 which permits the shaft G^3 to be rotated in the reverse direction to return the reservoir E to its initial position.

5 In order to raise or lower the pipe B^4 bodily toward or away from the band D , operating gear is provided and is diagrammatically illustrated in Fig. 1. This consists at one end of a link H pivoted at H^1 and having rigidly secured to it an operating arm H^2 . A link H^3 connects the tube B^4 and the free end of the link H . Pivotally connected to the operating arm H^2 is a link H^4 pivotally connected to another link H^5 which corresponds to the operating arm H^2 and has links H^6 and H^7 similar to the links H and H^3 respectively. It is obvious therefore that by moving the operating arm H^2 , the pipe B^4 will be raised or lowered according to the direction of the movement imparted to the operating arm H^2 .

10 The smoke-chamber is preferably covered with and ventilated by a raised lantern-roof A^4 .

15 25 In operation, latex is fed into the trough E^1 from the reservoir F until the outer surface of the band D just touches the surface of the latex and picks up a thin film. The gearing operated to elevate the reservoir F is so proportioned that latex is supplied to the trough at approximately the same rate that it is removed therefrom by the band D . The latex picked up by the band is carried thereby into the smoke-chamber which has 30 been heated by the incoming smoke to approximately 100° F. The smoke issuing from the orifices in the pipe B^4 impinges upon the trough C , thus largely eliminating moisture, naphthalene and smuts. The 35 smoke thus purified thereafter impinges upon the latex on the band D . As the band passes over the pulley D^1 , the tension thereon will tend to express water (combined with the latex) from the partially coagulated latex. Each revolution of the band 40 picks up a fresh layer of latex from the trough E^1 superimposing it upon the layer previously coagulated. The band, however, is prevented from sagging under the accumulated weight of the latex, by means of the tensioning weight D^8 and its connection with the pulley D^1 . After sufficient latex 45 has been coagulated upon the band, it may be removed therefrom by stripping off, as by the knife J , and immediately passed through the pressing rollers and then returned to the smoke-chambers for further 50 curing.

55 Preferably the smoke for curing latex is obtained by burning wood or leaves. As, however, in certain districts where latex is cured, the supply of wood or leaves is not very great, it is undesirable to use the smoke as the heating medium. The smoke-chamber 60 could be heated by steam or hot water

radiating in pipes K arranged inside the chamber and sufficient smoke need only then be added to cure the latex. Also it is not necessary that the heating and curing should be done in the same chamber as there might be arranged one chamber heated by any convenient means, and another chamber containing smoke into which the band subsequently travels.

70 It is found preferable to employ a band about 2 ft. wide and 42 ft. in length (over all). The latex is supplied to the band at such a rate that 12 gallons will be treated in 3½ hours, the temperature of the smoke-chamber being 100° F. This should allow 80 approximately 34-40 revolutions of the band per hour.

75 It is important that the supply of latex should be maintained at a distance from the smoke-chamber so that it shall remain cool and uncontaminated by smoke. Otherwise, it will be difficult to prevent the surface of the latex in the trough E^1 from coagulating. It is also important that the latex should not be allowed to drip from the reservoir but 85 should flow therefrom, also to prevent coagulation.

90 Although one particular method and apparatus have been described in detail for carrying the invention into effect, it is obvious that modifications may be made provided the spirit of the invention is not departed from. For instance, in place of the manually actuated crank-handle, a motor 95 could drive the shaft G^3 . Also several bands placed side by side could be driven from the same motor and could pass through the same smoke and heat chamber. It is found desirable in this case to arrange 100 a smoke or heating pipe or radiator under 105 each band.

95 What I claim as my invention and desire to secure by Letters Patent is:—

1. In an apparatus for curing latex, the combination of a supply receptacle; means 110 to draw said latex from said supply in a thin film; means to apply smoke to said film; means to apply heat to said film; and a closed chamber in which said heat and smoke means are located and into which 115 said film may be drawn during treatment, substantially as described.

2. In an apparatus for curing latex, the combination of a supply receptacle; means 120 having a motion of rotation and translation for drawing said latex from said supply in a thin film; means to apply smoke to said film while it is receiving its translating movement; means to heat said film while it is receiving its smoke treatment; and, a closed chamber in which said smoke and heat means are located and through which 125 said film may be drawn, substantially as described.

3. Apparatus for curing latex wherein it 130

is exposed in a thin film to the action of smoke and comprising in combination an endless band, a latex-containing receptacle through which the band passes, means for adjusting said receptacle in its relation to the band, and means for directing heat and smoke on to the latex picked up on the surface of the band.

4. Apparatus for curing latex wherein it is exposed in a thin film to the action of smoke and comprising in combination a latex-containing receptacle, a heat and a smoke-chamber, means for supplying heat and smoke to said chamber, an endless band passing through said receptacle and chamber, pulleys supporting the endless band, means for directing heat and smoke on to the latex picked up on the surface of the band, and means for expelling water from the coagulated latex.

5. Apparatus for curing latex wherein it is exposed in a thin film to the action of smoke and comprising in combination a heating and a smoke chamber a supply of latex situated outside thereof, an endless flexible band adapted to convey a thin film of material into said chamber, and a driving means for imparting motion to the band.

6. Apparatus for curing latex wherein it is exposed in a thin film to the action of smoke and comprising in combination a heating chamber containing smoke, a supply of latex situated outside of said chamber, a flexible endless band adapted to convey a thin film of material into said chamber, and a driving means for imparting motion to said band.

7. Apparatus for curing latex wherein it is exposed in a thin film to the action of smoke and comprising in combination a heating chamber, a supply of latex situated outside of said chamber, a flexible endless band adapted to convey a thin film of material into said chamber, a smoke generator, a smoke-delivering tube connected thereto and disposed under the endless band, and a driving means for imparting motion to the band.

8. Apparatus for curing latex wherein it is exposed in a thin film to the action of smoke and comprising in combination a heating chamber containing smoke, a vessel containing latex situated outside of said chamber, a flexible endless band adapted to convey a thin film of material into said chamber, mains to enable said band to remove continually the top layer of latex from the said vessel and a driving means for imparting motion to the band.

9. Apparatus for curing latex wherein it is exposed in a thin film to the action of smoke and comprising in combination a heating chamber containing smoke, a supply of latex situated outside of said chamber, a

flexible endless band adapted to convey a thin film of material into said chamber, a smoke purifier, and a driving means for imparting motion to said band.

10. Apparatus for curing latex wherein it is exposed in a thin film to the action of smoke and comprising in combination a heating chamber, a supply of latex situated outside of said chamber, a flexible endless band adapted to convey a thin film of material into said chamber, a smoke generator, a smoke-delivering tube connected thereto and disposed under said band and discharging smoke in a downward direction, a trough disposed below said smoke-delivering tube and upon which the smoke impinges, and a driving means for imparting motion to the band.

11. Apparatus for curing latex wherein it is exposed in a thin film to the action of smoke and comprising in combination a heating chamber containing smoke, a vessel containing latex situated outside of said chamber, a reservoir containing latex and supplying it to said vessel, a flexible endless band adapted to convey a thin film of latex into said chamber, a driving means for imparting motion to said band, and an operative connection between said driving means and the latex-reservoir to supply the latex-containing vessel with latex at the required rate.

12. Apparatus for curing latex wherein it is exposed in a thin film to the action of smoke and comprising in combination a heating chamber containing smoke, a vessel containing latex situated outside of said chamber, a reservoir containing latex and supplying it to said vessel, a flexible endless band adapted to convey a thin film of latex into said chamber, a driving means for imparting motion to said band, a screwed member secured to the latex reservoir, a nut engaging said screwed member and an operative connection whereby the nut is operated by the driving means to discharge latex from the reservoir into the latex-containing vessel at the required rate.

13. Apparatus for curing latex wherein it is exposed in a thin film to the action of smoke and comprising in combination a heating chamber, a supply of latex situated outside of said chamber, a flexible endless band adapted to convey a thin film of material into said chamber, a smoke-delivering tube disposed under said band and discharging smoke in a downward direction, a trough disposed below said smoke-delivering tube and upon which the smoke impinges and means to raise and lower the smoke-tube toward and away from the belt and driving means for imparting motion to the band.

14. Apparatus for curing latex wherein it is exposed in a thin film to the action of smoke and comprising in combination a

heating chamber containing smoke, a supply of latex situated outside of said chamber, a flexible endless band adapted to convey a thin film of material into said chamber, and means for maintaining the belt in tension, and a driving means for imparting motion to said band.

15. Apparatus for curing latex wherein it is exposed in a thin film to the action of
10 smoke and comprising in combination a heating chamber containing smoke, a supply of latex situated outside of said chamber, a flexible endless band moving in contact with the latex and adapted to convey a thin
15 film thereof into said chamber, a fixed pul-

ley at one end of said band, a movable pulley at the other end of said band, a movable bearing supporting said movable pulley, a flexible link connected at one end to said movable bearings, a weight secured at the 20 other end of said flexible link and a driving means for imparting motion to said band.

In testimony whereof I have signed my name to this specification in the presence of two subscribing witnesses.

ROBERT DERRY.
